SAW SET

Walter R. Williams, Sr., Danville, Ga.

Application December 9, 1938, Serial No. 244,836

1 Claim. (Cl. 76—69)

My invention relates to improvements in saw sets.

An important object of my invention is to provide a saw set that is adapted to clamp the saw blade in position and to set the various teeth thereof at the proper angle.

Another object of my invention is to provide a saw set that is adjustable to accommodate varying sizes of saws.

10 Yet another object of my invention is to provide a saw set that is simple in construction, efficient in operation and inexpensive to manufacture.

Other objects and advantages of my invention 15 will be apparent during the course of the following description.

In the accompanying drawings, forming a part of this specification, and in which like numerals are employed to designate like parts throughout 20 the same,

Figure 1 is a side elevation, partly in section, of a device embodying my invention, and illustrating the same in operative position,

Figure 2 is a side elevation thereof.

25 Figure 3 is an edgewise elevation of my device,

Figure 4 is an edgewise elevation of the body portion thereof,

Figure 5 is a vertical longitudinal sectional view taken on the line 5—5 of Figure 2,

30 Figure 6 is a fragmentary view illustrating the saw clamping means embodied by my invention,

Figure 7 is a transverse sectional view taken on the line 7—7 of Figure 6,

Figure 8 is a side elevation, partly in section, 35 of another form of my invention,

Figure 9 is a side elevation of the same and showing its association with a saw,

Figure 10 is a fragmentary edgewise elevation of the same,

40 Figure 11 is a transverse sectional view taken on the line 11—11 of Figure 8,

Figure 12 is a transverse sectional view taken on the line 12—12 of Figure 10,

Figure 13 is a fragmentary side elevation of 45 still another form of my invention, and

Figure 14 is a transverse sectional view taken on the line 14—14 of Figure 13.

While I have shown preferred embodiments of my invention in the drawings, it will be understood that various modifications are contemplated within the scope of my invention and I do not intend that my invention shall be limited to the particular forms shown.

Referring to Figures 1 to 7, inclusive, of the 50 drawings, the numeral 20 designates the body

portion having a saw-receiving slot 21. The head portion is formed with flat spaced side walls 22 having arcuated arms 23 extending upwardly therefrom and conjoined thereabove in a circular web 24. The body portion is conjoined at the ends 25 by the webs 25'. The web 24 is provided centrally thereof with a slot 26 through which extends a screw or bolt 27 carrying an anvil 28 interiorly of the said saw-receiving slot 21. The anvil 28 has a beveled edge 28' whereby the saw tooth is given the proper set. The bolt 27 is provided with a head 29 which is positioned in a countersunk opening in the anvil 28 in a manner to be flush with the inner face of the said anvil. The winged nut 30 is carried by the bolt 27 exteriorly of the web 24 to permit the adjustment of the said anvil with respect to the saw blade A. Pivoted between the side walls 22 is a pair of levers 31 and 32, which communicate at their inner ends with the said saw-receiving slot 21. The lever 31 terminates in a cam face 33, which operates in conjunction with and in a direction normal to the beveled face 28' of the anvil 28, as best illustrated in Figure 1 of the drawings. The lever 32 terminates in a transverse slot 34 in which is pivotally mounted a saw clamping member 35. Seated in the recess 31 is a spring 36 which bears on the under surface of the saw clamping member 35 to permit it to be yieldably adjustable 30 with the saw blade and to prevent the saw clamping member from crimping or substantially deforming the blade. As shown in Figure 2, the saw clamping member is normally closer to the flat holding face of the anvil than the cam face 33 is to the bevel working face thereof when the levers are in the open position. The levers 31 and 32 are provided with shanks 38 projecting from recesses 39 in which is seated the spring 40.

The operation of my device is as follows:

The saw blade A is inserted within the saw-receiving slot 21 of the head portion and the anvil 28 is properly adjusted within the slot 26 to properly coact with the cam 33 of the lever 45 31. The cam face 33 is shaped in a manner to contact the tooth of the saw evenly and firmly and does not press upon the beveled or sharpened edge of the tooth in a manner to dull or break the same. When the levers 31 and 32 are 50 brought together in operative position, the saw-clamping member 35 will first engage the plane surface of the saw blade and firmly hold the same against displacement before the cam face 33 of the lever 31 engages the beveled face of the 55

anvil 28 to properly set the tooth of the saw. The cams 35 and 33 move along lines normal to the flat and the beveled faces of the anvil, respectively, to evenly and firmly grip their respective portion of the saw blade. The spring 40 will force the levers 31 and 32 apart as soon as they are released, thereby preventing any jamming action from occurring between the saw-setting device and the blade of the saw.

10 In the form of my invention as illustrated in Figures 8 to 12 of the drawings, the head portion is a solidly formed block 41 having a saw-receiving slot 42 with spaced arms 43 extending outwardly and upwardly therefrom and terminating in a substantially circular web 44 through which extends a screw or bolt 45 carrying the anvil 46 which has a varying bevel 46' extending circumferentially around its bottom face to properly accommodate saws having varying shapes and sizes of teeth. The bottom lower portion of the block 41 is provided with bifurcated arms 47 between which are pivoted the levers 48 and 49 by means of the pin 50. The block 41 is provided with a forwardly positioned recess 51, which extends vertically from the web 44 and communicates with the saw-receiving slot 42 through the reduced portion 52. Within the recess 51 is a plunger 53 which terminates at one end in a saw-clamping block 54 disposed within the slot 42.

20 The opposite end 55 of the plunger 53 bears against the face 56 of the lever 48, and adjacent this end is provided an annular flange 57. A relatively weak spring 58 is interposed between the said annular flange 57 and the reduced portion 52 and functions to ordinarily maintain the saw-holding block 54 in a retracted position. The rear of the body 41 is provided with a diagonally disposed slot 59 in which is disposed the saw-setting plunger 60, one end of which extends through the reduced portion 51 into the saw-receiving slot 42 and coacts with the beveled working face 46' of the anvil 46. The opposite end 62 of the said plunger cooperates with the face 63 of the lever 49 and adjacent the end 52 is an annular flange 64. Disposed between the flange 64 and the reduced portion 51 is a relatively strong spring 65, which functions to ordinarily maintain the plunger 60 in a retracted position. As shown in Figure 8, a plunger 60 is axially movable along a line normal to the beveled working face of the anvil and the plug 54 is normally positioned closer to the flat holding face of the anvil than the inner end of the plunger 60 is to the beveled working face thereof.

30 In the operation of this form of my invention, the saw blade A is inserted in the saw-receiving slot 42 and the anvil 46 is rotated until the proper bevel is positioned in alignment with the saw-setting plunger 60. When the levers 48 and 49 are brought together, the inner faces 56 and 63 thereof will simultaneously coat with the ends 55 and 62 of the plungers 53 and 60. However, because of the relatively greater resistance offered by the spring 65, the handles will act to first bring the plunger 53 into clamping relation with the saw blade and to thereafter bring the plunger 60 into engagement with the tooth of the saw.

40 The form of my invention as illustrated in

Figures 13 and 14 is substantially the same as that illustrated in Figures 8 to 12 of the drawings. In this form the block 66 is provided with a head portion 67 which has a pair of bifurcated arms 68 embracing the upper portion of the block 66. Extending upwardly from the bifurcated arms 68 are arcuated extensions 69, which terminate in the substantially circular web 70. The anvil 71 having a constant beveled edge 72 is secured to the under side of the web 70 and within the saw-receiving slot 73. The plungers 74 and 75 cooperate with the cam faces of the levers 48 and 49 in the same manner as illustrated in the second form of my invention. The plunger 74 operates at right angles to the anvil 72, while the 10 saw-setting plunger 75 is provided with a right angularly disposed face 75' which operates at right angles to the beveled edge 72 of the anvil 71. Adjacent the lower ends of the plungers 74 and 75 and within the block 66 are transverse- 20 ly extending pins 76. A relatively weak spring 78 is interposed between the pin 76 of the blade holding plunger 74 and the upper end of the block 66, and a relatively strong spring 77 is interposed between the pin 76 of the tooth-setting plunger 75 25 and the block, which springs function to ordinarily maintain the plungers 74 and 75 in a retracted position.

The operation of this form of my invention is so similar to the second form that no further explanation is thought to be necessary.

It is to be understood that the forms of my invention, herewith shown and described, are to be taken as preferred examples of the same, and that various changes in the size, shape and arrangement of parts may be resorted to without departing from the spirit of my invention, or the scope of the appended claim.

Having thus described my invention, I claim:

A saw set comprising a body having a saw receiving slot, an anvil disposed within said slot and having a flat holding face and a beveled tooth setting face, a pair of axially movable plungers carried by the body each having a transverse anvil engaging end entering the said saw slot, 40 one of said plungers being arranged to travel normally to the holding face of the anvil and the other of the plungers being arranged to travel normally to the beveled tooth-setting face thereof, a pair of handle members lying athwart each 50 other and connected to the body by a common pivot, parts of the handles extending at opposite sides of the pivot and engaging the ends of the plungers remote from the anvil, and spring means arranged within recesses in the body and around 55 the said plungers, one end of the springs abutting against the body and the other end thereof contacting parts of the plungers in a manner to hold the plungers normally retracted, the said spring coacting with the tooth-setting plunger being relatively stronger than the spring coacting with 60 the saw holding plunger whereby actuation of the handle members will act to first move the saw holding plunger into engagement with the holding face of the anvil and to thereafter move the tooth-setting plunger into engagement with the beveled tooth-setting face thereof.

WALTER R. WILLIAMS, SENIOR.
